TWO-SHEET DETECTOR

August C. Smith, Pittsburgh, Pa., assignor to
Miller Printing Machinery Company, Pittsburgh, Pa., a corporation of Pennsylvania

Application April 24, 1937, Serial No. 138,807

6 Claims. (Cl. 271—56)

This invention relates to printing presses and in particular, to means for stopping the feeding of blank sheets to the press in case more than one sheet is simultaneously picked up from the pile at the feeding end.

The feeding of more than one sheet at a time to high-speed presses causes a great deal of difficulty even after the press has been stopped by automatic throw-out means operable in response to the feeding of two sheets, for example. It is the object of my invention, therefore, to provide means for preventing the usual sheet feeding means from feeding a plurality of sheets to the press at a time, whereby to avoid this difficulty.

In accordance with my invention, I provide a relatively fixed abutment past which the sheets being fed to the press are moved. A movable member adapted to cooperate with the fixed abutment is moved toward the latter during a portion of the passage of each sheet therewith, defining a gap through which a single sheet will pass freely. The fixed abutment is preferably adjustable so that the precise spacing between it and the movable member may be obtained, depending upon the thickness of the sheets being handled. If two sheets should be fed simultaneously they are gripped between the fixed abutment and movable member and prevented from being fed forward to the press. The press is then automatically thrown out by known means, operated on failure of the delivery mechanism to advance a sheet at the proper time.

A clear understanding of the invention may be gained from the following detailed description thereof, which is to be read in connection with the accompanying drawing illustrating a present preferred embodiment. In the drawing

Figure 1 is a view largely diagrammatic, showing partly in side elevation and partly in section, the various elements comprising the invention; and

Figure 2 is a fragmentary view to a large scale showing a portion of the apparatus illustrated in Figure 1.

As indicated in outline in Figure 1, sheets are adapted to be lifted from a pile 10 supported on a delivery table 11 by suction feet (not shown) and when so lifted, transferred laterally of the pile by transfer suckers 12, for delivery to the press. The movement of the transfer suckers is indicated by the dotted line showing of the alternate position thereof. The details of the feed table and the sheet lifting and transfer mechanism are well known and thus do not require further explanation.

A shaft or supporting bar 13 extends between the usual side frames of the press and supports a downwardly extending bracket 14. A spring finger 15 is secured to the lower end of the bracket by screws 16. The position of the free

end of the spring relative to the lower end of the bracket 14 may be adjusted by means of a thumb screw 17 threaded through the bracket and bearing on the upper side of the spring. The screw 17 is provided with a lock nut 18 to hold it in adjusted position.

The presser foot 19 is mounted on the upper end of a thrust rod 20. The finger 15 and pressure foot 19 form a pair of gripper jaws or calipers between which the sheets are passed and which, as hereinafter pointed out, are yieldingly moved toward each other with sufficient force to seize and arrest the feeding movement of the sheets in case two or more sheets are simultaneously passed between them. The rod 20 is slidable through a guide bearing 21 carried on a bracket 22 secured to vertical guide bars 23 forming part of the feed table. The guide bearing 21 is positioned so that on vertical movement of the rod 20 the foot 19 approaches the finger 15 and is disposed in about the same vertical plane as the latter.

The rod 20 is urged upward by a compression spring 24 disposed between the guide bearing 21 and a set collar 25 on the rod 20. A stop 25a limits upward movement of the rod.

A cam lever 26 is tiltable on a shaft 27 mounted in any convenient manner in the press frame. The right hand end of the lever 26 is provided with a clevis 28 having a tapped bore adapted to receive the lower threaded end 29 of the rod 20. A lock nut 30 secures the rod in adjusted position relative to the clevis.

The left hand end of the lever 26 is provided with a follower roller 31 cooperating with a cam 32. The cam is keyed to a shaft 33 journaled in the press frame and driven by any convenient means in synchronism with the operation of the press and, therefore, the sheet feeding means 12. The cam 32 has a recessed portion 34 covering about 90° of its periphery. The remainder of the cam has a substantially uniform radius. The position of the cam on the shaft 33 and the speed of rotation of the latter are determined so that the cam lever 26 will effect a complete tilting cycle each time a sheet is fed from the pile 10 to the press, and preferably the cam is so positioned that the recess 34 thereof will engage the roller 31 shortly after the sheet being fed has advanced past the finger 15.

In the operation of the apparatus, the finger 15 is first adjusted by turning the screw 17 so that when the foot 19 is in its uppermost position (shown in Figures 1 and 2), the space therebetween will freely pass a single sheet from the pile 10. The adjustment is made close enough, however, so that should two sheets be lifted and fed simultaneously from the pile, the foot 19, because of the double thickness thereof, will press them against the finger 15 tightly enough to

prevent them from being fed forward further. Under such circumstances, the transfer suckers 12 simply slide off the edge of the sheet.

The complete operating cycle is as follows:

- 5 With the foot 19 in its lowermost position, the suction feet engage the top sheet of the pile and lift it therefrom for engagement by the transfer suckers 12. Shortly after the latter have moved the leading edge of the sheet beyond the finger
- 10 15, the cam 32 permits the spring 24 to shift the lever 26 and raise the rod 20 and the foot 19 to the illustrated position. If only one sheet has been lifted from the pile and fed forward therefrom, it will pass freely between the finger and the foot and continue to move with the suckers 12. After a relatively short period, the rotation of the cam 32 restores the lever 26 to its normal position and depresses the rod 20 and the foot 19 against the force of the spring 24. This leaves
- 15 ample space between the finger 15 and the foot 19 for the free passage of the sheet without any drag or restraining effect whatever thereon. As a matter of fact, there is only very little or no restraint placed upon the sheet when the foot is
- 20 25 in its uppermost position.

If two sheets should simultaneously be lifted from the pile, the double thickness thereof will cause the foot 19 on reaching the upper extremity of its movement, to press the sheets firmly against the finger 15 with the result that forward movement thereof is arrested and the transfer suckers 12 slide off the leading edge. The successive feed of sheets being thus interrupted, the automatic means for throwing-out the press 35 comes into play and the press is immediately stopped.

It will be recognized that the removal of two sheets from between the finger 15 and the foot 19 is a relatively simple matter so that the press can be restarted with very little delay. This is not true if the two sheets are permitted to reach the press and be fed therewith. The advantages of the invention from the standpoint of the avoidance of time loss resulting from the accidental lifting and feeding of two sheets instead of one 40 will be readily recognized. The invention, furthermore, is simple and inexpensive in construction so that it adds very little to the cost of construction or maintenance of the press.

Although I have illustrated and described but one preferred embodiment of the invention, it will be understood that changes in the construction disclosed may be made without departing from the spirit of the invention or the scope of the appended claims.

I claim:

1. In a sheet-feeding apparatus, the combination with means for releasably seizing a sheet from a pile and moving it to a point laterally thereof, of a relatively fixed abutment adjacent the path of the sheet, a presser foot adapted to cooperate with said abutment and effective therewith to grip and restrain a plurality of sheets against feeding movement should they be seized and moved simultaneously, and means operating during the passage of each sheet past the presser foot for moving the foot into a gripping position relative to said abutment such that the movement of a plurality of sheets is arrested.
- 60 65 70 2. In a sheet-feeding mechanism, means for feeding sheets from a pile, grippers between which the fed sheets are passed, normally so separated as to permit free passage of the sheets

between them, adjustable means for limiting the movement of the grippers toward each other to leave a gap between them greater than the thickness of one sheet but less than that of two sheets, and means operating as a sheet is fed past the grippers for moving the grippers toward each other with sufficient force to seize a plurality of sheets and arrest their feeding movement should they be fed simultaneously.

3. In a sheet feeding-mechanism, means for feeding sheets from a pile, grippers between which the fed sheets are passed, normally so separated as to permit free passage of the sheets between them, adjustable means for limiting the movement of the grippers toward each other to leave a gap between them greater than the thickness of one sheet but less than that of two sheets, and yielding means operating after the leading edge of a sheet has been fed past the grippers for urging the grippers toward each other with sufficient force to seize a plurality of sheets and arrest their feeding movement should they be fed simultaneously.

4. In a sheet-feeding mechanism, means for feeding sheets from a pile, grippers between which the fed sheets are passed, normally so separated as to permit free passage of the sheets between them and having a limited movement toward each other to leave a predetermined gap between them only wide enough to permit the passage of but a single thickness sheet between the grippers, and means for moving the grippers toward each other after the leading edge of a sheet has passed the grippers and for then separating them before the trailing edge of the sheet reaches the grippers, said means acting to move the grippers together with sufficient force to clamp and hold against feeding movement two or more sheets fed together in multiple thickness.

5. In a sheet-feeding mechanism, means for feeding the sheets, grippers between which the fed sheets are passed normally so separated as to permit free passage of the sheets between them, means for limiting the movement of the grippers toward each other to leave a gap of predetermined width between them, and means operating periodically as the sheets are fed past the grippers for moving the grippers toward each other with sufficient force to seize and arrest the feeding movement of the sheets should the thickness thereof exceed the gap setting of the grippers.

6. In a sheet-feeding mechanism, means including a transfer sucker for lifting the top sheet from a pile and moving it laterally, a relatively fixed gripper jaw past which the sheets are successively fed, a movable gripper jaw cooperating therewith, a stop for limiting the movement of the movable jaw to leave a gap between the jaws sufficient for the passage of a single sheet only, a spring for urging the jaws together with sufficient force to grip and hold a plural thickness of sheets against the lateral feeding movement, and means for holding the jaws apart against the force of the spring when the leading edge of a sheet is fed past the jaws, for then allowing the spring to move the jaws together to permit a single sheet to be fed but to hold a plural thickness of sheets against movement until the transfer sucker has moved beyond the held sheets, and for thereafter again holding the jaws apart as the trailing edge of a fed sheet passes between them.

AUGUST C. SMITH.
